United States Patent Office

Des. 208,887
Patented Oct. 10, 1967

208,887

SHINGLE

Donald M. Gillis, Los Angeles, Calif.
(7770 Hollywood Blvd., Hollywood, Calif. 90046)

Filed July 19, 1966, Ser. No. 3,131

Term of patent 14 years

(Cl. D68—1)

FIG. 1 is a top perspective view of a shingle, embodying my new design; and

FIG. 2 is a bottom perspective view thereof.

I claim:

The ornamental design for a shingle, substantially as shown.
